GAME APPARATUS TO TEST DEXTERITY

Max Tiarks, Herford, Germany, assignor to Patterson International Corporation, Cincinnati, Ohio, a corporation of Ohio

Filed Jan. 6, 1966, Ser. No. 497

Term of patent 14 years

(Cl. D34—5)

Fig. 1

Fig. 2

Fig. 3

FIGURE 1 is a view in plan elevation of my game apparatus to test dexterity showing my new design.

FIGURE 2 is a view in side elevation of my game.

FIGURE 2 is a view in side elevation of my game.
FIGURE 3 is a view in end elevation of my game.

The dominant features of the design reside in the portions shown in full lines.

I claim:

The ornamental design for a game apparatus to test dexterity, as shown and described.
